UNITED STATES PATENT OFFICE

172,393

FLASHLIGHT-OPERATED BOAT RUNNING LIGHT

Hugo F. Keller, Oneida, N. Y.

Application April 16, 1953, Serial No. 24,532

Term of patent 7 years

(Cl. D48—20)

To all whom it may concern:

Be it known that I, Hugo F. Keller, a citizen of the United States, residing at Oneida, State of New York, have invented a new, original, and ornamental Design for a Flashlight-Operated Boat Running Light, of which the following is a specification, reference being had to the accompanying drawing, forming a part hereof.

Figure 1 is a side elevational view of a flashlight-operated boat running light, showing my new design;

Figure 2 is a top plan view thereof;

Figure 3 is an end elevational view thereof, looking at the left end of the running light in Figure 1; and

Figure 4 is an end elevational view thereof,

looking at the right end of the running light in Figure 1.

The broken lines shown in Fig. 1 indicating a flashlight are for illustrative purposes only.

I claim:

The ornamental design for a flashlight-operated boat running light, as shown and described.
